OF KNOXVILLE, TENNESSEE

IRONING BOARD OR TABLE

Application filed April 29, 1930. Serial No. 448,260.

The present invention relates to those ironing boards or tables which are adapted to fold into relatively compact and flat condition so that they will occupy only a small space when not in use.

5 My object is to provide, in an ironing board or table of the class described, first, an improved combination of board, upright legs, inclined legs and board support or brace; second, in an improved combination aforesaid, a brace which may be engaged with the board at different points of the 10 lengths thereof so that the board may be supported at both ends when ordinary ironing is being carried on, or, the brace may be made to engage with the board considerably 15 farther inwardly from the narrow end thereof, to enable the smaller end of the board to freely project, adapting it to be used as a skirt board or for the ironing of tubular articles of apparel; a third object is to provide, in an ironing board or table, an 20 improved folding tray or laundry support located below the ironing table in position conveniently to hold the laundry which is intended to be ironed so that the ironer will have her work handily disposed; the fourth 25 object is to provide an improved foldable ironing board or table comprising a novel combination of board, upright legs, inclined 30 legs, foldable brace adapted to engage the ironing board at different points of the length thereof, and a laundry holder, rack, or tray disposed below the ironing board, all of 35 said parts being combined so that they may be readily collapsed into compact arrangement, or extended to comprise the complete table.

A practical embodiment of the invention 40 is hereinafter described and is disclosed in the accompanying drawings, in which:

Figure 1 is a perspective view showing the table set up and ready for use;

Fig. 2 is a similar view showing the table 45 collapsed for storage;

Fig. 3 is a detailed perspective view showing the notch and reinforcement for one of the side rails of the laundry rack;

50 Fig. 4 is a detailed perspective view show-

ing the joint for the inclined legs, side rails and braces;

Fig. 5 is a perspective view looking toward the bottom of the ironing board, disclosing the cleats which engage the brace;

Fig. 6 is a perspective view of the brace; and

Fig. 7 is a perspective view, the parts being broken away, showing the rear of the board, the rear legs, and the upper ends of the inclined legs forming the joint for said parts.

The ironing board or table appears at 1, being provided on its undersurface with cleats 2, 10, the former being disposed in the region of the tapered end of the board, and the latter somewhat rearwardly thereof, the purpose of these cleats appearing hereinafter.

The rear or upright legs are shown at 8, the inclined legs appear at 6, the shiftable brace is designated 3, and the improved 70 clothes tray, rack or laundry holder is shown at 7 as having the slats 14.

The upper ends of the rear or upright legs 8, the rear, upper ends of the inclined legs 6, and the back hinge piece 16 which is secured to the under side of the board 1, are pivoted together on lag screws 12 so that folding of the legs 6 and 8 against the bottom of the board 1, may be effected, as shown in Fig. 2.

The forward ends of the side rails of the 80 tray or laundry rack, the forward parts of the inclined legs 6, and the lower ends of the brace 3 are pivoted or hinged together by a rod 5, as illustrated in Fig. 4 so that the brace 3 may be positioned, as shown in Fig. 85 1, in engagement with the notched ends of the cleat 2, or, swung rearwardly to engage the cleat 10 when the ironing board is to be used as a skirt or sleeve board, as the rearward disposition of the brace 3, against cleat 10, leaves 90 the outer tapered end of the board 1 free for insertion within any tubular garment which has to be ironed.

When in ordinary use as an ironing board or table, the parts are in the arrangement 95 shown in Fig. 1.

When folded, the brace or leg 3 folds down inside the tray 7, alongside the side rails thereof, and on the slats 14, the notches 9 in the side rails of the tray then being disen-

gaged from the lower cross-piece which connects the rear legs 8. When folded, the rear legs 8 are disposed outside of the inclined legs 6, as shown in Fig. 2.

5 Referring to Fig. 6, it will be seen that the upper, free ends of the brace 3 are pointed so that they can readily engage the notches in the cleat 2 and thus prevent any sidewise displacement of the board 1. The braces 4 and 17 render the hinged brace 13 rigid.

Referring to Fig. 8, it will be seen that the rear legs 8 have braces 11, additional to the lower brace 13 (Fig. 1), to strengthen these legs and afford stability.

10 15 Referring to Fig. 3, there is a steel dowel pin 15 which extends across the rear end of the side rails of the laundry tray 7 so that there is no danger of splitting off of the notched ends of said side rails, due to strain or pressure.

20 As set up in Fig. 1, the ironing board or table is arranged for the usual ironing operations. By shifting the brace 3 rearwardly to cause it to engage the front edge of the cleat 10, the forward part of the ironing board 1 is thus cleared of obstruction so that it may be used as a skirt or sleeve board.

25 Whether set up for use as a skirt or sleeve board, or for ordinary use, the tray or rack 7 having the slats 14, constitutes an important part of my invention. The tray 7 serves as a convenient holder for the wash which is to be ironed and, due to the relationship of the inclined legs 6 to the said tray, the wash is retained on the tray and yet there is no part which obstructs free access to the wash to prevent it from being readily handled, piece by piece, for ironing on the board 1.

30 35 The laundry tray or rack 7 also serves as a horizontal brace and, in connection with the legs 8, legs 6, and brace 3, provides a rigid supporting structure for the board 1 so that regardless of the weight or pressure put on the board, the entire ironing table is rigid.

40 45 When the ironing board is collapsed, as shown in Fig. 2, it occupies but very little wall or closet space, enabling it to be readily stored.

50 What I claim is:

1. In a foldable ironing board or table, the combination with an ironing board, of rear upright legs hinged thereto, inclined legs hinged to the rear upright legs, a single pivot rod connecting the inclined legs together and located between the lower ends of said inclined legs and the point where said inclined legs are hinged to the rear upright legs, a tray pivoted on said single rod at one end and at its other end having means for its detachable connection to the upright legs, and a front brace whose lower end is pivoted to the aforesaid single pivot rod and whose upper end is engageable with the ironing board at different points of the length thereof, said upright legs, tray, inclined braces and front

brace being adapted to be folded flatwise against the bottom of the ironing board.

2. In a foldable ironing board or table, the combination with an ironing board, of rear upright legs hinged thereto, inclined legs hinged to the rear upright legs, a single pivot rod connecting the inclined legs together and located between the lower ends of said inclined legs and the point where said inclined legs are hinged to the rear upright legs, a tray permanently pivoted on said single rod at one end and at its other end having a hook-like form by which it is detachably engaged with the upright legs, and a front brace whose lower end is permanently pivoted to the aforesaid single pivot rod and whose upper end is engageable with the ironing board at different points of the length thereof, said upright legs, tray, inclined braces and front brace being adapted to be folded flatwise against the bottom of the ironing board.

In testimony whereof I affix my signature.

JAMES LENVILLE BROWN.
